G. Martz,

Elevator,

N° 12,633,

Patented Apr. 3, 1855.

Fig. 1.

UNITED STATES PATENT OFFICE.

GEORGE MARTZ, OF POTTSVILLE, PENNSYLVANIA.

APPARATUS FOR HOISTING AND DUMPING COAL-CARS.

Specification of Letters Patent No. 12,633, dated April 3, 1855.

To all whom it may concern:

Be it known that I, GEORGE MARTZ, of the borough of Pottsville, in the county of Schuylkill and State of Pennsylvania, have 5 invented a new arrangement of the fixtures for perpendicular hoisting as applied to the hoisting of coal-cars out of shafts or from one elevation to another where the coal is required to be dumped or emptied from such 10 coal-car, by which the car unloads itself and readjusts after so doing, so that it can return to the place of starting without the intervention of manual labor, and by which the car is protected from falling in case the 15 rope or chain by which it is suspended breaks; and I do hereby declare that the following is a full, clear, and exact description of the construction, and operation of the same; reference being had to the annexed 20 drawings, making a part of this specification, of which—

No. 1 is in perspective. In this drawing the portions marked "A" represent the guides and outside frame that always keep a 25 vertical position; the parts marked "B" represent the tipping or dumping carriage and frame inside of the guides and outside frame.

The car is marked "C."

Those portions marked "D" represent a 30 carriage of a construction now ordinarily used for perpendicular hoisting of coal cars from shafts, having one guide (marked A¹) on each side of the "shaft," and a rope or chain from the point "E" in a cross piece 35 in frame attached to this carriage and going over a pulley wheel at top of "shaft" to the hoisting power. This carriage and frame is called the "hoisting carriage and 40 frame." The scaffold marked "F" is fixed to this "hoisting carriage" by means of posts, and run about one half of the length of the carriage; on it are fixed by means of an axle two wheels marked "G." This hoisting 45 carriage, frame and scaffold do not alter their position in reference to the guides and shaft, but are raised up and let down by the hoisting power as required.

The carriage and frame marked "B" is 50 called the "tipping or dumping carriage and frame." This carriage rests on the two wheels marked "G" (which wheels by preventing friction allow it to run easily for-

ward when required for the purpose of tipping) and also on the ends of two iron arms 55 marked "H" which are fastened in the other ends by an axle to the center of the hoisting carriage as seen in the drawing, but to the one side of the center of gravity of the coal car when it stands on the "tipping carriage." To the tipping carriage these arms are fastened on the other side of the center of gravity of the car (it being the side toward which the car tips when unloading) thus giving to these arms, a small inclination 60 from the perpendicular toward the side on which the car tips, these arms when the car is in a horizontal position being against the end of the scaffold "F" and thus held in 65 position.

The blocks marked "T" and fastened to the tipping frame by means of levers marked "K" are so arranged that when the car is at the bottom of the shaft they are drawn out from between the wheels of the car by the 70 ends of the levers resting on catches "L" made for the purpose which raises them up thus leaving the car free ready to be pushed away, but when the car raises to the elevation of the catches, the blocks "I" have 75 dropped between the wheels of the car, and hold it in its place while going up the shaft and while tipping or dumping. The extra guide "A²" gives direction to the guide wheels "M" which being connected to the 80 "tipping carriage and frame holds them in their places while being hoisted up the shaft. These guide wheels "M" when the car is being hoisted up will bear upon the extra guide "A²" owing to the car being fastened to the iron arms as above described, and for the same reason on arriving at the 85 top of the shaft the guide wheels "M" following the curved guide "N" will carry the car forward toward the "dumping or tip 90 chute" "O," and the falling of the arms "H" while the end of the car rests on the wheels "G" will give it the requisite inclination 95 for emptying the coal or substances in the car, on the opening of the door which is 100 effected by a small projection on the side of the chute catching the bolt of the door, and forcing it up out of the catch.

The length of the hoisting carriage is so graduated that when the car is tipped sufficiently the tipping frame rests on it thus 105

giving tipping fixtures a bearing sufficient for the requisite steadiness and also allowing them to be raised up on this position with safety should they be hoisted 5 higher than necessary.

On returning the guide wheels "M" following the curved guides "N" throw the car and tipping carriage and fixture back in a horizontal position and the car returns to 10 its place at the bottom of the shaft ready to be taken away and reloaded.

If a car loaded with any material not required to be dumped is hoisted, by dropping the false guides "I" the car is raised up in 15 a horizontal position and by throwing out a rest marked "R" the hoisting carriage can be let down on it, and by ketches similar to those at the bottom of the shaft the blocks "I" will be raised by the levers from be- 20 tween the wheels of the car, and it be left

free ready to be taken away on a track made for the purpose.

What I claim as my invention and desire to secure by Letters Patent, is—

The combination of the coal car C, and its carriage B, with the hoisting carriage D, in such a manner that whilst the hoisting carriage D, is guided vertically up the shaft by its ways A¹, the carriage of the coal car C, is guided by the independent ways A², and N, in such a manner as to tilt the car, when it attains the proper elevation, and place it in such a position that its contents will be self discharged into the chute O, substantially as herein set forth. 25 30

GEORGE MARTZ.
